UNITED STATES PATENT OFFICE.

DANIEL MELCHER, OF BONESTEEL, SOUTH DAKOTA.

DROP-MOVEMENT FOR TRIP-HAMMERS.

SPECIFICATION forming part of Letters Patent No. 739,331, dated September 22, 1903.

Application filed August 30, 1902, Serial No. 121,629. (No model.)

To all whom it may concern:

Be it known that I, DANIEL MELCHER, a citizen of the United States, residing at Bone-steel, in the county of Gregory and State of South Dakota, have invented a new and useful Drop-Movement for Trip-Hammers and the Like, of which the following is a specification.

This invention is an improved construction of drop-movement particularly adapted for trip-hammers, drilling machinery, and similar mechanisms where a quick and sudden drop is desired.

The object of the invention is to provide an exceedingly simple and highly efficient device by means of which the weight to be raised can be evenly elevated and suddenly dropped without subjecting the mechanism to any sudden or unusual jar.

Another object of the invention is to provide a construction in which the parts liable to wear can be quickly and easily replaced whenever necessary.

With these objects in view the invention consists in the novel features of construction and combination hereinafter fully described, and pointed out in the claims.

In the drawings forming a part of this specification, Figure 1 is a perspective view illustrating the practical application of my invention. Fig. 2 is a sectional elevation illustrating the initial movement of the double cam upon the single cam. Fig. 3 is a view illustrating the position of the cams at the end of the elevating operation; and Fig. 4 is a detail perspective view of the single cam, illustrating the detachable heel-piece.

In order to show the practical application of my invention, I have illustrated only so much thereof as is necessary to explain the relative positions and operations of the several elements, and by referring to the drawings it will be noted that I have arranged the mechanism upon a main frame comprising side beams A, the intermediate beams A', end beams B, and the uprights or standards C, between which is journaled the shaft or beam D, to which the walking-beam E is connected.

Mounted upon a shaft I and between one of the intermediate and the side beams is a double cam K, said cam having two curved

faces and two straight faces, the straight faces being provided with metallic face-plates K', the outer ends of which project a short distance beyond the ends of the cam-blocks, as most clearly shown at K².

L indicates a single cam mounted upon a shaft L', which is journaled upon the main frame, said cam having a single curved surface which is adapted to contact intermittently with both of the curved surfaces of the double cam K. Upon the inner end of the shaft L' is a crank-arm M, to which the lower end of the pitman N is connected, the upper end of said pitman being pivotally connected to the walking-beam, as most clearly shown. Upon the outer end of said shaft is a brake-wheel O, having a brake-lever P held in contact therewith by means of a spring Q, the brake-wheel O being essentially in the form of a ratchet-wheel, the purpose being to prevent any backward movement of the cam-shaft L'. The heel of the cam L is cut out to receive a metallic heel-plate L², which has a shoulder L³, adapted for engagement with the projecting end K² of the face-plate K'.

In operation one member of the double cam K bears down upon the single cam L, rotating the same, and in so doing the crank-arm M is carried around, elevating the pitman N, and consequently the walking-beam. The start of this movement is indicated in Fig. 2, and owing to the shape of the cams the said movement will be very gradual, so that the power will be greatest at the point where it is needed most—namely, at the beginning of the elevation of the working parts—and at such time speed can readily be sacrificed for the power obtained. By the time the end of the cam K reaches the heel of the cam L the projecting end K² engages the shoulder L³, and at the same time the crank-arm M passes beyond the perpendicular, and the moment the crank-arm passes beyond the perpendicular the pitman, walking-beam, and all parts connected thereto drop by their own weight, there being nothing whatever to check the drop, and the toe of the cam L is again brought around ready for engagement with the second section of the cam K, so that at each revolution of the cam K the cam L will be operated twice. The cam-faces are preferably smooth, thereby insuring a steady action, and by hav-

ing the face-plates K' and the heel-piece L² detachable the said parts can be quickly and easily removed and replaced whenever they become worn. It will thus be seen that I provide an exceedingly simple and highly efficient drop mechanism and one in which any form of driving power may be employed.

Having thus fully described my invention, what I claim as new, and desire to secure by 10 Letters Patent of the United States, is—

1. In a mechanism of the kind described, the combination with the double arm having face-plates upon the flat faces thereof, a single cam having a heel-plate provided with a 15 shoulder, the ends of the face-plates being

adapted to engage said heel-plate, substantially as set forth.

2. In a device of the kind described, the combination of the main frame, walking-beam, and a double cam mounted upon the 20 frame, said double cam having face-plates, a single cam having a metallic heel-piece provided with a shoulder, the crank-arm connected to the shaft of the single cam, the pitman connected to said crank-arm and to the 25 walking-beam, substantially as described.

DANIEL MELCHER.
